CLAIM

The ornamental design for the tall book display rack, as shown and described.

DESCRIPTION

FIG. 1 is an isometric view of the tall book display rack of this invention;

FIG. 2 is a top view thereof;

FIG. 3 is a right side view, the left side view being a mirror image thereof;

FIG. 4 is a front view thereof;

FIG. 5 is a bottom view thereof;

FIG. 6 is a back view of the invention; and,

FIG. 7 is a cross-sectional view of the rack, at its midpoint, from its front to the back thereof.
